UNITED STATES PATENT OFFICE.

EDWARD BIGNELL, OF LINCOLN, NEBRASKA, ASSIGNOR OF TWO-FIFTHS TO HARRY T. JONES, OF SEWARD, NEBRASKA.

NOZZLE FOR PILES AND CAISSENS.

1,089,525.

Specification of Letters Patent.

Patented Mar. 10, 1914.

Application filed May 31, 1913. Serial No. 770,936.

To all whom it may concern:

- Be it known that I, EDWARD BIGNELL, a citizen of the United States, residing at Lincoln, in the county of Lancaster and State of Nebraska, have invented certain new and useful Improvements in Nozzles for Piles and Caissons, and have described the same in the following specification, illustrated by the accompanying drawings.
- 10 My invention relates in general to that class of subsurface structures, such as piles, sheet piling and caissons, commonly formed of concrete or other cohesive and adhesive material, which are sunk by gravity and by 15 the action of water under pressure, in excavations made by themselves while sinking, and are utilized as foundations for wharves, piers, bridges and other superstructures to be supported thereby.
- 20 It relates in particular to the lower or terminal nozzles of such subsurface structures. Nozzles of this class, as heretofore constructed, usually fail to produce at the foot of the sinking substructure an excavation sufficiently large in horizontal sectional area to receive that substructure, and also to permit the upward flow of water and commingled earth around and at the sides of the structure sunk therein.
- 25 To obviate this common fault is the object of this invention. To accomplish this object, I incorporate in a substructure of this class, or affix thereto, a terminal nozzle which divides the excavating current, descending 30 through the middle of the structure, into two separate streams, one driven vertically into the earth below, and the other driven obliquely upward and outward along the under surface of the structure.
- 35 In the accompanying drawings, illustrating the best manner in which I have contemplated applying the principles of the invention, Figure 1 is a sectional elevation of a pile which is constructed in accordance with 40 these principles. Fig. 2 is a central vertical section of a portion of a caisson, constructed in accordance with the same principles. Fig. 45 3 is a central vertical section of a portion of a pile or caisson, having a nozzle constructed 50 in a modified form in accordance with these principles.

The illustrative pile shown in Fig. 1 is of the general construction and mode of operation disclosed in Letters Patent of the

United States, No. 1,024,820, which were issued to me April 30, 1912, for improvements in piling construction. The body, or stem 1, of this pile, is formed of concrete, or other cement, and is of uniform horizontal section, either circular, square or polygonal. It has a longitudinal axial opening 2, which is lined with a metallic pipe 3, to be supplied with water under pressure. It has also a plurality of branch openings 4, which extend horizontally outward in radial directions from the opening 2 and through the sides of the stem 1, and are lined with the metallic pipes 5, branching from the pipe 3. As in said Letters Patent, this pile has also a rotatable tubular shaft 6, disposed vertically in the pipe 3, and forming a water conduit in communication with the terminal nozzle member 7, and the lower nozzle member 8, which are united by the screw bolts 9 and are spaced by the sleeves 10 on those bolts. The nozzle member 7 is an annular plate convex below and having a central annular boss 9', which engages the end of the pipe 3 by a screw thread and is co-axially and detachably united with the lower end of the stem 1 by any convenient means. The nozzle member 8 is a concavo-convex plate thicker at the middle than at the edges and having a central orifice 10', smaller than the pipe 6, and co-axially registering therewith for the discharge of an excavating stream vertically downward. This nozzle member 8 is somewhat larger in diameter than the plate 7, and smaller than the stem 1. The distance between these plates is greatest in the middle and diminishes toward their edges; whereby the concavo-convex water space between them, being the flaring upper outlet 11 of the nozzle, is vertically contracted toward its circumference, and rendered tapering in vertical section as shown. The least cross-sectional area of the lower outlet 10', plus the corresponding area of the upper outlet 11 of this nozzle, is equal to, or slightly less than the cross-sectional area of the water pipe 6.

The illustrative caisson, shown in Fig. 2, comprises the cylindrical shell 12, having the side nozzles 13, the annular and outwardly convex bottom shell 14 peripherally united with the shell 12, the central vertical water pipe 3' joined to the bottom shell, and the annular chamber 15 which is formed between the shells and the water pipe. The

terminal nozzle of this caisson, being a modification of the lower nozzle shown in Fig. 1, comprises the lower nozzle member 16, and, as an upper nozzle member, the 5 middle portion of the bottom shell 14, which are united by a plurality of sleeve bolts. The nozzle member 16 resembles intrinsically the above described nozzle member 8 of Fig. 1, but differs therefrom in being 10 bolted immediately to the bottom of the caisson, which serves as an upper nozzle member. This construction prevents the adhesion of soil to the bottom of the caisson.

The nozzle shown in Fig. 3, differs from 15 that shown in Fig. 2, in having its lower nozzle member 16' diametrically larger than the bottom 14' of the pile or caisson, and in being bent upward at its periphery; whereby its discharge is directed upward around 20 the sides of that substructure.

In the operation of this invention, the 25 stream of water from between the nozzle members is driven upward along the sides of the structure in the form of a hollow cylinder of water, aiding the descent of the structure by lubricating its entire peripheral surface, and also by exerting a reverse downward thrust upon the lower nozzle member.

I claim as my invention.

1. In a substructure of the specified class, 30 a terminal nozzle comprising an annular plate detachably united with the bottom of the substructure, and an annular downwardly convex plate fastened to the first mentioned plate in a co-axial position and 35 spaced therefrom.

2. In a substructure of the specified class, 40 a terminal nozzle comprising an annular plate united with the bottom of the substructure, and an annular downwardly convex plate fastened to the first mentioned plate in a coaxial position and spaced apart therefrom.

3. In a substructure of the specified class, 45 a terminal nozzle comprising a downwardly convex annular plate united with the bottom of the substructure, and an annular concavo-convex plate fastened to the first mentioned plate in a coaxial and subjacent position, and spaced apart therefrom. 50

In testimony whereof I hereunto subscribe my name in the presence of two witnesses.

EDWARD BIGNELL.
